UNITED STATES PATENT OFFICE

RALPH M. MESSINGER, OF TOLEDO, OHIO

DESIGN FOR A COMBINED DISPLAY AND VENDING CASE

Application filed October 6, 1930. Serial No. 37,146. Term of patent 3½ years.

To all whom it may concern:

Be it known that I, RALPH M. MESSINGER, a citizen of the United States, and resident of the city of Toledo, county of Lucas, and State of Ohio, have invented a new, original, and ornamental Design for a Combined Display and Vending Case, of which the following is a specification, reference being had to the accompanying drawing, forming a part thereof.

In the drawings,

Fig. 1 is a perspective view of the case showing my new design; and

Fig. 2 is a rear end view of the upper portion of the case.

I claim:

The ornamental design for a combined display and vending case as shown.

In testimony whereof I have hereunto signed my name to this specification.

RALPH M. MESSINGER.
